(57) **CLAIM**

The ornamental design for a ceiling fan switch control tool, as shown and described.

DESCRIPTION

FIG. 1 is a front elevation view of a ceiling fan switch control tool showing my new design, the rear elevation view being a mirror image;

FIG. 2 is a right side view thereof;

FIG. 3 is a left side elevation view thereof;

FIG. 4 is a top plan view thereof, the bottom plan view being the same but inverted;

FIG. 5 is an isometric view of the ceiling fan switch control tool, wherein the tool is engaging an on/off switch on a ceiling fan; and,

FIG. 6 is an isometric view of the ceiling fan switch control tool, wherein the tool is engaging a pull chain for a ceiling fan. The broken lines in FIGS. 5 and 6 of the drawings depict environmental subject matter only and form no part of the claimed design.
